UNITED STATES PATENT OFFICE

JAMES WHITE, OF WEBB CITY, MISSOURI, ASSIGNOR OF ONE-HALF TO ROY R. COYNE,
OF WEBB CITY, MISSOURI.

MEANS FOR CONNECTING SHELLS TO CORES OR HUBS.

1,282,341.

Specification of Letters Patent. Patented Oct. 22, 1918.

Application filed December 15, 1916. Serial No. 137,184.

To all whom it may concern:

Be it known that I, JAMES WHITE, a citizen of the United States, residing at Webb City, in the county of Jasper and State of Missouri, have invented a new and useful Means for Connecting Shells to Cores or Hubs, of which the following is a specification.

This invention relates to crushing rolls. The invention is especially applicable to crushing rolls used in mines for crushing dirt and ore, where the outer portions or shells of the rolls soon become damaged and it is necessary to replace the same. By replacing or renewing the outer portion only of the roll a great saving is insured.

The object of the invention is to provide a construction whereby the outer portion or shell of the roll may be easily and quickly removed from or replaced upon the inner portion, hub or core of the roll.

The above object is achieved by utilizing a tapered hub and a shell having a tapered seat fitting over the hub and providing a special construction of groove and lug by which the several parts are interlocked. Blocks or plugs may also be used to keep out of the grooves dirt and foreign material, which would interfere with the easy separation of said parts.

The invention will be best understood from a consideration of the following detail description, taken in connection with the accompanying drawing, forming part of this specification with the further understanding that while the drawing shows a practical form of the invention, the latter is not confined to any strict conformity with the showing of the drawing, but may be changed and modified, so long as such changes and modifications come within the scope of the appended claims.

In the accompanying drawing I have illustrated one embodiment of my invention on a reduced scale, in which:

Figure 1 is a perspective view of a roll with parts broken away to more clearly illustrate the invention;

Fig. 2 is a transverse sectional view 50 through the roll;

Fig. 3 is a sectional view on the line 3—3 of Fig. 2;

Fig. 4 is a sectional view on the line 4—4 of Fig. 2; and

Fig. 5 is a detail side view of the hub or core.

In the embodiment of the invention here illustrated the hub or core 1 which is made in one piece is tapered, as clearly shown in Fig. 5. The reduced end of the core is indicated by the reference character 2, and the enlarged end thereof by the reference character 3. The core is fixed in any suitable manner to the shaft 4, which may be mounted in suitable bearings upon the framework 60 of the crushing engine which has not been illustrated, inasmuch as it forms no part of the present invention.

Extending inwardly from the reduced end of the core or hub 1 and upon the periphery thereof are substantially L-shaped grooves 5 and 6. These grooves are spaced equi-distantly around the circumference of the hub. Each groove comprises a portion or branch 7 extending inwardly from the reduced end 2 of the hub and toward the opposite end 3, as clearly shown in Fig. 5. The inner portion or branch 8 of the groove is bent, extends circumferentially of the hub, and obliquely to the axis thereof and 80 projects toward the enlarged end 3 of the hub. The obliquely arranged portion 8 of each groove is provided with sides 9 and a closed end 10. The portions 8 of the grooves also extend around the hub in the same direction circumferentially and gradually taper toward the closed ends 10.

The outer portion or shell 11 of the roll is cast in one piece and is provided with a tapered seat or central bore 12 having a reduced end 13, and an enlarged end 14, as shown in Figs. 3 and 4. Projecting inwardly from the inner periphery of the shell and within the bore are lugs 15 and 16, which are arranged at diametrically opposite points and are adapted to register with and slide within the portions 7 of the grooves. It will be seen that, as the shell is placed upon the hub with the lugs registering with the grooves, the axial movement thereof upon the hub will be limited by reason of the fact that the lugs will engage the sides 9 facing the portion 7 of the grooves. The hub and shell are then rotated

5 relatively to each other, whereby the inclined sides 17 of the lugs engage the sides 9 to the left, as shown in Fig. 1, exerting a cam or wedging action thereupon which causes the shell to be moved tightly and snugly upon the tapered hub and to be locked thereon, the lugs engaging the ends 10 of the grooves and are wedged in the tapered portions of the latter.

10 It will be apparent that the wedging of the shell upon the hub and the wedging of the lugs in the tapered portions of the inner branches of the grooves effects a double wedging action of the shell upon the hub, 15 and thereby tightly and securely fastens said shell in place.

When the shell has been thus located upon the hub, plugs 18 are inserted into the portions 7 of the grooves and prevent the access of dirt and foreign matter to the 20 grooves whereby the danger of clogging the same, thus preventing the easy removal of the shell, is obviated.

It is preferable, when operating, to rotate 25 the hub or core in the direction indicated by the arrow, Fig. 1, whereby the ends 10 of the grooves engage the lugs 15 and 16 and cause the shell to rotate in the same direction, thereby preventing the slipping of 30 the shell around the hub as an axis.

It is thought that the operation and the manner in which my invention may be manipulated to separate and to unite the several parts of the roll will be apparent from 35 the above description and needs no further elaboration.

The plugs 18 perform the additional function of retaining the lugs 15 and 16 in the branches 8 of the grooves.

40 What is claimed is:

1. In a device of the character described, a tapered one-piece hub, and a one-piece shell having a tapered seat for the hub, said parts being detachable, the hub having a plurality of L-shaped grooves, each groove comprising a portion extending inwardly from the smaller end thereof lengthwise of the hub, and a portion extending obliquely to the axis of the hub and circumferentially thereof and forming a continuation of the

first portion, the obliquely disposed portion being tapered in the direction of its outer end, said shell having a plurality of fixed lugs, each lug having sides arranged obliquely to the axis of the hub, and adapted 55 to slide in the first portion of said groove and wedge in the second portion, whereby the parts are interlocked and the shell is drawn snugly upon the tapered hub.

2. In a device of the character described, 60 a tapered one-piece hub, a one-piece shell having a tapered seat for the hub, said parts being detachable, the hub having a groove comprising a portion extending inwardly from the smaller end thereof and a portion 65 extending obliquely to the axis of the hub and circumferentially thereof and forming a continuation of the first portion, the obliquely disposed portion being tapered in the direction of its end, the shell having a 70 fixed lug projected to slide in the first portion of said groove and wedge in the second portion, whereby the parts are interlocked and the shell is drawn snugly upon the tapered hub, and a separate plug inserted in 75 said first portion of the groove and extending into the second portion of said groove.

3. In a device of the character described, 80 a tapered one-piece hub, a one-piece shell having a tapered seat for the hub, said parts being detachable, the hub having a groove comprising a portion extending inwardly from the smaller end thereof and a portion 85 extending obliquely to the axis of the hub and circumferentially thereof and forming a continuation of the first portion, the obliquely disposed portion being tapered in the direction of its end, the shell having a fixed lug projected to slide in the first portion of 90 said groove and wedge in the second portion, whereby the parts are interlocked and the shell is drawn snugly upon the tapered hub, and a separate plug inserted in said first portion of the groove and extending into the second portion of said groove, the said lug 95 having its inner end arranged obliquely to the axis of the hub.

In testimony that I claim the foregoing as my own, I have hereto affixed my signature.

JAMES WHITE.
